UNITED STATES PATENT OFFICE.

THEODOR SCHÄFFER, OF HELLERUP, DENMARK.

HAND-SETTING MECHANISM FOR CLOCKS.

SPECIFICATION forming part of Letters Patent No. 726,994, dated May 5, 1903.

Application filed February 5, 1900. Serial No. 4,054. (No model.)

To all whom it may concern:

Be it known that I, THEODOR SCHÄFFER, a subject of the King of Denmark, residing at Hellerup, Denmark, have invented certain new and useful Improvements in or Relating to Hand-Setting Mechanism for Clocks, (for which I have applied for patents in Denmark, No. 710/99, dated August 5, 1899; in Germany, No. 14,983, dated August 14, 1899; in Norway, No. 11,460, dated September 2, 1899; in Sweden, No. 1,327, dated September 2, 1899; in Austria, dated September 10, 1899, and in Hungary, No. 12,361, dated September 12, 1899,) of which the following is a specification.

The invention relates to an electric hand-setting mechanism by means of which the hands of a number of secondary clocks placed at different places at fixed times can be set from a primary or standard clock placed at a central station. The invention is characterized thereby that the hands of the secondary clocks at the moment adjustment is to be effected are released from the axle by means of an armature attracted by an electromagnet, which armature simultaneously brings the hands into such a position that when the electromagnet releases its armature the hands, which then are again connected with the axle, are in true accordance with the position of the hands of the primary or standard clock.

The accompanying drawings illustrate the invention.

Figure 1 is a front view of parts of a clock provided with the new hand-setting mechanism. The dial and the hands are omitted and some parts are cut away in order to better show the other parts. Fig. 2 is a side view of the clockwork, showing the position of the parts when the magnets are deenergized. Fig. 3 is a side view of some parts of the clockwork. The electromagnet has attracted its armature, so that the hands are released from the axle and may be set. Fig. 4 shows a detail of the hand-setting mechanism.

The minute-hand axle *a* of the clock is rotated as usual in ordinary clocks. The minute-wheel *b* is fixed loosely on the axle, and its hub has a tubular part *c*, which incloses the front end of the axle. The minute-hand

is fixed to the tubular part *c* of the hub and must consequently rotate with the minute-wheel. In front of the minute-wheel and firmly attached to this is a minute-hand pinion *d*. The hour-hand pinion *g* is rotated from the minute-hand pinion *d* by means of pinion *e*, on the axis of which is fixed a pinion *f*, engaging pinion *g*. The pinion *g* has a tube-shaped hub *h*, which incloses the tubular part *c* of the minute-wheel hub and to which is fixed the hour-hand. The minute-wheel is connected to the axle *a* by means of a friction-disk *i* rotating with the axle, but longitudinally movable on it. The disk *i* is normally forced toward the rear side of the minute-wheel, thereby forcing this wheel, its tube-shaped hub *c*, and the parts fixed to it to revolve with the axle. Below the axle is placed a pair of electromagnets *j*, whose armature *k* is mounted loosely on an axle *l*, placed between the electromagnets in such a manner that it (the armature) can rotate around said axle and move longitudinally on it. To the armature is fixed a fork *m*, extending upward, and, further, a screw *n*, which acts as a counterweight, which when the armature is not attracted by the electromagnets brings the armature, and thereby the fork *m*, into the normal position shown in dotted lines, Fig. 1. The electromagnets are included in an electric circuit through the standard clock at the central station, which circuit will be more fully explained.

To the front plate of the clock-frame at *o* a lever *p* is pivotally connected. A spiral spring *r*, adjustably connected at its rear end to the rear plate of the clock-frame, has its forward end connected to the upper end of said lever and tends to tilt the same on its pivot, pushing the lower end of the lever away from the plate of the clock-frame. This lever depends in vertical alignment with arbor and spindle and is provided with openings in horizontal alignment with said parts to permit of the passage thereof through the lower part of the lever. The lever carries a truncated cone *q*, slideable on arbor, which is designed when the lever is tilted to press disk *i* firmly against minute-wheel *b*, which causes said wheel to rotate with said disk, the latter, as before stated, being splined to arbor *z*, as shown at 2. During this period the lower

end of the lever p of course holds the armature away from the magnets. When the magnets are energized, they attract the armature, as before stated, which forces the lower end 5 of lever p toward the front plate against the tension of spring r . The movement of lever p carries the cone q out of contact with disk i , so that the frictional engagement between the latter and minute-wheel b is broken. The 10 disk i then turns independently, leaving the minute-wheels and the parts controlled thereby free to be adjusted.

The electromagnets are included in a circuit s , Fig. 1, connected to earth at t and connected to the line u , leading to the circuit of the standard clock, by means of a switch v and a contact w on the circumference of the minute-wheel, against which contact the contact-spring x of the switch is forced when the 15 circuit s is to be closed through the line u . The circumference of the minute-wheel is of insulating material and is only provided with said contact-point w . The circuit s is therefore only closed when the contact-spring x touches contact w . Switch v is capable of turning on a 20 pin fixed on a plate y , Fig. 1, which is insulated from the clock-frame, and switch v is kept in such a position by a spring z that the contact-spring x does not normally touch the 25 circumference of the minute-wheel. Firmly attached to the upper part of the switch, but insulated therefrom, is a tooth a' , which during the revolution of the hour-hand wheel is 30 operated by pins or projections o' on the front 35 of this wheel, thereby turning the switch and forcing the spring x against the circumference of the minute-wheel. In the present example are shown three of these pins o' , having equal intervals on the pinion g , which is 40 making one revolution in twelve hours, and this contact-spring x will consequently be forced toward the circumference of the minute-wheel every fourth hour, closing the 45 circuit as soon as it touches the contact-point w . If at this moment a current is sent through the line u , then the electromagnets j are energized and attract the armature, thereby releasing the hands, which then may be 50 adjusted on the axle. This adjustment is effected by means of the fork m , fixed to the 55 armature. When the armature k is attracted by the electromagnet, it will also be turned on axle l , so that it comes into a horizontal position. The fork m is thereby 60 brought into the position shown in full and dotted lines, Fig. 1, engaging the pin l on the back of the minute tube-wheel and moving it, and thereby the minute-wheel b , which, as stated in this moment, is loose on axle a , into 65 a predetermined position.

The mechanism operates in the following manner: It is supposed that the clocks connected with the central station are to be adjusted every fourth hour—say, at four, eight, 65 and twelve o'clock—and it is also supposed that contact w is of such a size that it closes contact for two minutes and that the pins o'

are placed in such a manner that they at the appointed hour move contact-spring x into contact with the circumference of the minute-wheel, on which contact w is so placed that the contact between spring x and contact w will commence one minute before and be maintained until one minute after the above-named hours. The standard clock 70 closes the line-circuit ten seconds before the above-named full hours, thus sending a current through the line. Supposing that the clock to be adjusted is one minute too fast, then spring x will still be on contact w , and consequently circuit s will be closed, thus bringing into activity the electromagnets. These will attract and turn the armature k , causing the release of the hands. At the same time the fork m is brought in engagement with the 75 pin d , thereby bringing it and the hands into the position determined by the situation of the pin d on the minute-wheel—i. e., on the stated full hour. After the ten seconds—i. e., at full hour—the standard clock breaks off 80 the circuit through the line. Consequently the electromagnets j release the armature k , and all parts return at once into their normal positions, and the hands, which are now set by the standard clock, are again turned by 85 the clockwork-axle a . After four hours the circuit is again closed and the adjustment 90 repeated as stated above. The adjustment may consequently also be effected at other times than the above named, in which case 95 only is required that the position of the hands is changed with regard to the contact-point w . The armature k being loose on the shaft l , pressure of the spring r exerted through the lever p will hold the armature at the outer 100 end of the said shaft, and when the magnets are energized the armature will both turn on said shaft and move longitudinally thereon, 105 overcoming in the latter movement the pressure of the spring r .

What I claim is—

1. In combination, a rotating arbor, a minute-wheel loosely mounted thereon, hour-hand mechanism controlled thereby, means rotating with the arbor, a lever for holding said wheel, an electromagnet, an armature controlled thereby, said armature when attracted, 115 tilting said lever to break the friction engagement with the minute-wheel, and means 120 carried by the armature engaging said wheel to set the same, said armature having a rotary motion in addition to the movement which tilts the lever, substantially as described.

2. In combination, a main arbor, a minute-wheel, loosely mounted thereon, hour-hand mechanism controlled thereby, a friction-clutch interposed between said wheel and arbor, a rotating and shifting armature, means 130 controlled by the shifting of the armature for releasing said clutch and means operated by the rotation of the armature for setting said minute-wheel, substantially as described.

3. In combination, a main arbor, a minute-wheel loosely mounted thereon, a friction-disk keyed to the arbor engaging said wheel, a pivoted lever for shifting said disk, an electromagnet, and armature therefor, having a rotary and a shifting movement longitudinal of its axis, said armature coöperating with said lever in the latter movement to control said friction-disk, an arm carried by said armature and a pin on said minute-wheel with which said arm coacts, whereby said minute-wheel is set, substantially as described.
4. In combination, a main arbor, a minute-wheel loose thereon, an hour-wheel pinion rotated thereby, a friction-clutch coöperating with said wheel, an electromagnet, an armature therefor controlling said clutch, means

carried by said armature coöperating with the minute-wheel to set the same and an electric circuit comprising a wire, leading to said electromagnet, a switch interposed in said line, a contact located on the periphery of the minute-wheel, and means carried by the hour-pinion for shifting said switch into engagement with said contact to close the circuit to the magnets, substantially as described. 20
